(57) **CLAIM**

The ornamental design for an electronic vaporizer as shown and described.

DESCRIPTION

FIG. 1 is a front perspective view.

FIG. 2 is a back perspective view.

FIG. 3 is a front view.

FIG. 4 is a back side view.

FIG. 5 is a right side view.

FIG. 6 is a left side view.

FIG. 7 is a top view; and,

FIG. 8 is a bottom view.

The broken lines in the drawings depict portions of the electronic vaporizer that form no part of the claimed design.
